UNITED STATES PATENT OFFICE.

HERMAN IHLENBURG, OF PHILADELPHIA, PENNSYLVANIA, ASSIGNOR TO THE
MACKELLAR, SMITHS & JORDAN COMPANY, OF SAME PLACE.

DESIGN FOR A FONT OF TYPE ORNAMENTS.

SPECIFICATION forming part of Design No. 22,007, dated November 22, 1892.

Application filed October 28, 1892. Serial No. 450,291. Term of patent 7 years.

To all whom it may concern:

Be it known that I, HERMAN IHLENBURG, a citizen of the United States, and a resident of Philadelphia, Pennsylvania, have invented a new and original Design for a Font of Combination Type Ornaments, of which the following is a specification.

My design for a font of combination type ornaments is fully illustrated in the accompanying typographical impression, in which the various types numbered 1 to 25 are shown detached, together with a series of examples showing how the various types may be combined to form an entirety.

The leading features of the design are the twisted spindles and the scrolls and squares imitating wrought-metal work.

The characters numbered 9, 11, 12, 21, 22, 23, 25, 26, and 35 are corner characters proper, the characters 14, 15, 16, 17, 18, 20, 29, 30, and 33 are tail-pieces used in finishing out a line, and the remaining characters are center pieces used for making up the sides and for filling out a line to any length desired.

The distinctive characters 5, 13, 27, and 28 represent twisted spindle work, and the characters 19, 20, 23, 24, 30, 32, 33, and 35 represent wrought-metal work, the curves and scrolls being in plain black lines, as clearly shown in the accompanying impression. The several characters shown can be set up and formed in many different styles of frames, borders, lines, &c., as clearly shown in the impression.

I claim—

The design for a font of combination type ornaments, substantially as described, and as shown in the accompanying typographical impression.

In testimony whereof I have signed my name to this specification in the presence of two subscribing witnesses.

HERMAN IHLENBURG.
